THERMAL MOLECULAR ALTERATION OF
CARBON COMPOUNDS

Percy H. Royster, Bethesda, Md.

Application October 3, 1942, Serial No. 460,658

3 Claims. (Cl. 196—55)

1

This invention relates to the art of thermally altering the molecular constitution of carbon compounds and is concerned with improvements in such processes and with apparatus adapted for use in the carrying out of such improved processes. Thus, the invention contemplates improvements in the cracking of hydrocarbon oils such, for instance, as crude petroleum, gas oil, fuel oil, kerosene, or petroleum residues, whereby to produce hydrocarbon oils such, for instance, as gasoline or gasoline-containing cracked distillates, having lower molecular weights and/or lower boiling points than the starting materials. It specifically contemplates a process for the commercial production of a lower boiling product such as motor fuel and in particular a low boiling point motor fuel exhibiting high anti-knock properties. The invention contemplates also a treatment of hydrocarbon gases such as natural gas, methane, ethane, ethylene, propane, and the like, and mixtures thereof, particularly non-condensable gases formed in "cracking" petroleum in present refinery practice, whereby to form hydrocarbons of higher boiling points than the starting materials. Further, it contemplates improvements in processes of thermally treating hydrocarbons of any molecular weight whereby to effect a change in molecular constitution by such thermal means, in the presence or absence of catalysts, as well as to subjecting the hydrocarbons to thermal and chemical treatments wherein reactions involving oxidation, reduction, hydrogenation, hydration, dehydration, and the like, may take place.

An object of the present invention is the provision of an improved thermal process whereby reactions may be carried out more efficiently at elevated temperatures and at pressures varying from commercial vacua to the upper extremes of high pressures. Another object of the invention is the provision of an improved process for the production of modern anti-knock motor fuel from crude petroleum, distillery intermediates, and residues. The provision of an improved process for the hydrogenation under suitable pressures of less marketable refinery products is another objective. An improvement in the so-called "reforming" of natural gas, methane, ethane, or the like, with steam to form hydrogen and carbon monoxide is still another objective.

In general it is the object of this invention to provide an improved method by which a thermally unstable fluid may be subjected to a thermal treatment at a carefully controlled

2

temperature for a controlled period of time, whereby to produce a substantial amount of a second fluid, which itself is unstable at the thermal treatment temperature, without concurrent material thermal destruction of said second fluid. Included among the objects of invention is the provision of apparatus peculiarly adapted for use in carrying out "cracking" and similar thermal treatment processes, which apparatus may be constructed more cheaply than that heretofore used for these purposes.

The general process of the present invention is as follows: through the interstices of a mass of heat-absorbing particles, enclosed in a thermally insulated chamber, there is forced a carrier gas heated to an elevated temperature T_2 (T_2 being at least equal to the alteration temperature), the passage of the heated carrier gas being continued until an appropriate temperature distribution is established in the mass; thereafter, a stream of the fluid to be treated, at a temperature T_0 (i.e., below thermal alteration temperature) is passed at a controlled rate of speed through the interstices between the heated particles of the mass, whereby the temperature of the fluid is raised from T_0 to a chosen reaction temperature T_1 and the desired thermal alteration is initiated, the time of contact between the heated particles of the mass and the stream of fluid to be treated being so controlled that the stream of fluid is maintained at temperature T_1 for a period of time just sufficient to allow the desired thermal alteration to proceed to a satisfactory extent; and the fluid immediately thereafter is cooled to a temperature T_3 at which continued thermal alteration does not materially proceed. In the carrying out of this process, control of the rate of flow of the fluid to be treated through the mass of heated particles preferably is so determined with respect to the volume, density, space-distribution of temperature, and shape of said mass that each part or portion of the stream of fluid is, by passage thereof through the heated mass, heated to the desired thermal alteration temperature and not materially thereover and is maintained thereat for the proper time interval of thermal alteration.

It is a feature of this invention that the assemblage of heat-exchanging solid particles is so designed as to make possible "isochronous flow" of the stream of fluid therethrough, by which latter expression I mean that each portion of the fluid stream remains in heat-exchanging contact with the heat-exchanging solid particles

for the same period of effective time. A unit of "effective time" at any given temperature lower than T_1 is defined as the length of time in which the same reaction takes place in one second at T_1 . When this special type of uniformity of fluid flow (i. e., "isochronous flow") is realized, the proper interval of heat-exchanging contact between the stream of fluid and the pre-heated solid particle mass is readily attained and maintained by appropriately controlling the rate of flow of the total stream of fluid; if the effluent product is found to contain excessive amounts of decomposition products of the altered substance, time of contact has been too long and, to correct this fault, the rate of fluid flow is increased; if the content of altered substance in the effluent product is found to have diminished, the time of contact has been too brief and accordingly the rate of fluid flow is diminished. Such a method of control can only be attained satisfactorily where the time intervals of passage of the several portions of the stream of fluid are substantially the same; that is, when the paths are isochronous or substantially so.

The invention will be described in greater detail in the following illustrative but not restrictive examples, taken in conjunction with the accompanying drawings, in which:

Fig. 1 is a diagrammatic showing of an apparatus for carrying out a process embodiment of the invention;

Fig. 2 is a graph illustrative of temperature distributions within a reaction chamber of the apparatus of Fig. 1 during the carrying out of the process;

Fig. 3 is a diagrammatic showing of a modified apparatus for carrying out a modified process in accordance with this invention;

Fig. 4 is a graph illustrative of temperature distributions within a reaction chamber of the apparatus of Fig. 3 during the carrying out of the modified process; and

Figs. 5 and 6 are diagrammatic showings of further modified apparatus in accordance with this invention.

Illustration 1

An embodiment of the present invention from the standpoints both of process and of apparatus will now be described with reference to Figs. 1 and 2.

In Fig. 1, the reference numeral 1 represents any suitable oil supply container, 2 represents a variable-speed oil pump, 3 represents a suitable heat-exchanger of the tube type, and 4 represents a suitable pipe heater, these four pieces of apparatus being connected in the order named by suitable conduits provided with suitable valves. 5 represents a manifold conduit connecting pipe heater 4 with each of the three similar reaction chambers A, B and C through suitable oil vapor inlet valves 6a, 6b, and 6c, respectively. Each of reaction chambers A, B and C is a thermally-insulated, gas-tight vessel provided with suitable openings: in each is an open space (illustrated in chamber A at 7a) at the bottom, above which are suitable grates or other supports (8a in chamber A) upon which is supported a mass of promiscuously deposited, relatively small, solid heat-exchange bodies, e. g., pebbles (9a in chamber A), above which mass is an open space (10a in chamber A). Chambers A, B and C may be so designed that the aforesaid masses of heat-exchange solids are relatively broad for their

height—e. g., even broader than high—where low pressure drop is a technical desideratum.

In appropriate openings adjacent the tops of chambers A, B and C and in communication with their upper open spaces (10a in chamber A) are arranged appropriate branches of manifold conduit 11 controlled by the valves 11a, 11b and 11c, respectively, which conduit 11 communicates with the interior of heat-exchanger 3. 12 represents a suitable cooler, connected by suitable piping with heat-exchanger 3 and with product storage tank 13.

The reference numeral 14 represents a steam line, in communication with a source of steam (not shown), with branches 14a, 14b and 14c, controlled by valves 15a, 15b and 15c, respectively, in communication respectively with the upper open spaces 10 (10a in chamber A) of chambers A, B and C.

The reference numeral 15 represents a suitable air heater into which air under pressure can be forced by blower 16 connected thereto. From air heater 15 extends manifold conduit 17 with branches 17a, 17b and 17c, controlled by valves 18a, 18b and 18c, respectively, in communication with the upper open spaces 10 (10a in chamber A) of chambers A, B and C, respectively.

From the lower open spaces (7a of chamber A) of chambers A, B and C extend conduits 19a, 19b and 19c, controlled, respectively, by valves 20a, 20b and 20c, which conduits 19a, 19b and 19c either discharge into a chimney (not shown) or directly into the atmosphere.

As a definite illustration, a crude petroleum (38° A. P. I., 300 lbs./bbl.) with an initial boiling point of 207° F., distilling a 23% naphtha fraction below 337° F. and a 35% crude kerosene fraction between 337° and 572° F., is forced by oil pump 2, at the rate of 73 bbls./min. through heat exchanger 3 and thence through pipe heater 4 in which it is heated to 700° F., i. e. below cracking temperature. The so preheated oil flows from pipe-heater 4 through conduit 5 and open oil vapor inlet valve 6a and enters open space 7a below grate bars 8a and thence passes upwardly through a mass of superimposed pebbles 9a. Pebble mass 9a is cylindrical, 24 ft. 9 inches in diameter, and has an axial dimension of 15 ft. Its volume is 7,350 cu. ft. This mass, consisting of pebbles screened between 1" and 1½", weighs 109 lbs. per cu. ft., and shows a 38.8% volume of voids. The total weight of 9a in chamber A is 800,000 lbs. At the beginning of the described operation these pebbles are heated at the substantially uniform temperature 1000° F., i. e., at cracking temperature.

The actual flow of preheated petroleum vapor, as it enters pebble-mass 9a is 83,000 cu. ft./min., measured at entrant conditions (13 cm. Hg gauge pressure, 700° F.) for an oil having an average molecular weight of 190. Hence the mean upward velocity of vapor through the interstices between the pebbles is 7.45 ft./sec. The time of transit through pebble mass 9a would be 2.00 seconds were the specific volume of the fluid unchanged during transit; however, its specific volume is changed in the following respects: The temperature of the petroleum vapor increases in passage through mass 9a from 700° to 1000° F. whereby its volume is increased 25 per cent. With reduction in the mean molecular weight from 190 for the vapor before treatment to 142 for the vapor after treatment, the vapor volume is increased a further 25 per cent due to the cracking reaction. Assuming an irreducible minimum decomposition

of cracked product during formation sufficient to form 2% solid carbon, and a simultaneous production of 2.6% by weight of "fixed" gases, the vapor volume is increased 55 per cent from this cause. The decrease in pressure experienced by the stream in transit causes an increase of only 17%. The total effect of these four causes, temperature-rise, molecular change, formation of fixed gases, and drop in pressure, is to increase the rate of flow of petroleum by volume from 83,000 cu. ft./min. at the point of entrance into pebble mass 9a to about 197,000 cu. ft./min. at the point of leaving the same. The velocity of the fluid stream is 13.6 ft./sec. at the top of pebble mass 9a compared with 7.3 ft./sec. at the bottom of the mass. The average velocity for the whole path is 10.5 ft./sec., and the time required for the fluid to traverse pebble mass 9a is 1.42 seconds, including the time consumed by the vapor in passing through space 10a and manifold conduit 11. Where the crude petroleum stock used for this illustration exhibits characteristics similar to the Grosny crude used by Sachanov and Tilicheev ("Petroleum," vol. 23, page 521, 1927), the rate of production of motor fuel is 45.4% per second at 1000° F. Since the mean yield of "cracked product" in the experiments of Sachanov and Tilicheev was 64.5%, it is seen that the flow of 73 bbls./min. permits completion of the cracking reaction to take place just as the fluid completes its transit through pebble mass 9a. The vaporous product emanating from pebble mass 9a rises into open space 10a above said mass and passes from reaction chamber A into conduit 11 and thence through heat exchanger 3 and into cooler 12 and is cooled to below thermal alteration temperature immediately after the completion of the reaction; thereby "over-cracking" (due to too long exposure to high temperature) is largely avoided. In heat exchanger 3 the vaporous product indirectly imparts heat to the incoming crude petroleum.

The operation takes place as described above only at the beginning of the passage of the fluid stream through pebble mass 9a. Petroleum vapor at the rate of 21,900 lbs./min. enters pebble mass 9a at 700° F. Each pound of oil requires 216 B. t. u. to raise its temperature from 700° to 1000° F. Hence 4,740,000 B. t. u./min. are transferred from pebble mass 9a to the fluid stream and the pebbles themselves are cooled to 700° F. When 129 barrels of crude petroleum ("129 barrels throughput") have been forced into reaction chamber A (a stage in operation designated epoch I) the temperature distribution in pebble mass 9a is as shown in curve a of Fig. 2, in which the vertical distance above the grids 8a (designated x) is plotted as abscissae and temperature (in degrees Fahrenheit) is plotted as ordinates. In heating 129 barrels of oil from 700° F. to 1000° F., 61,000,000 B. t. u. is removed from the pebbles in the lower part of mass 9a, a quantity of heat represented in Fig. 2 by the area between curve a and the 1000° isotherm. At Epoch I, the mean temperature of 9a is less than at the beginning of the operation and it is obvious that insufficient time of contact would be permitted to realize the completion of the cracking reaction if the flow rate of 73 bbls./min. were maintained. This flow rate is therefore continuously diminished at a controlled rate from the beginning of the operation and when epoch I has been reached is reduced to 34 bbls./min., which permits the oil vapor in transit to remain in pebble mass 9a for

3.04 seconds. When 258 barrels of feed-stock have been forced into chamber A (epoch II), the temperature of pebble mass 9a is as shown in curve b in Fig. 2. Curves a and b are similar except that curve b is shifted to the right (in the figure upwardly in the apparatus) 3.75 feet and

$$10 \quad \left(\frac{\delta T}{\delta x} \right)$$

for curve b is less than for curve a. The maximum temperature gradient for curve b is 48° F. per foot and for curve a is 67° F. per foot. The fluid flow is continuously diminished after epoch I and at the end of epoch II it has been reduced to 17.4 barrels/min. to permit completion of the cracking reaction within pebble mass 9a and open space 10a. At 515 barrels throughput (epoch III) temperature distribution in 9a is given as curve c in Fig. 2. The appropriate oil flow at Epoch III is 19 bbls./min. At this point the cracking operation is preferably terminated. The isothermal region at 1000° F., which was present from the beginning through epochs I and II, has practically vanished at epoch III, and further immediate operation in reaction chamber A is unprofitable.

From the beginning of the operation to the end of epoch III, the rate of oil flow was diminished continuously from an initial maximum flow of 73 bbls./min. to the final minimum of 10 bbls./min. The rate of flow of the fluid at each intermediate epoch was adjusted in relation to the temperature at each portion of pebble mass 9a and the length of time each portion of the fluid remained at each such temperature was so controlled that the "cracking reaction" reached completion just as the vaporous product completed its passage through 9a, 10a and 11. In this way "over-treatment" and "under-treatment" are both avoided.

The previously described operation in chamber A is termed "on stream."

Reaction chamber A is then taken "off stream" and the cracking process terminated at epoch III. Valves 6a and 11a, Fig. 1, are closed. Steam from steam-line 14 through opened steam-valve 15a traverses chamber A downwardly from open space 10a to open space 7a sweeping residual petroleum from mass 9a, and discharges through opened purge valve 21a which, with purge valves 21b and 21c, connects (through suitable conduit not shown) with cooler 22, in which latter both petroleum and the steam are condensed, the petroleum separated from the condensed steam being collected in purge collector 23 for further use. Concurrent with the above purging step in chamber A, reaction chamber B, already heated to 1000° F., is placed "on stream" and the operation described above for chamber A is repeated for chamber B, valves 6b and 11b being opened.

When petroleum vapor has been purged from chamber A by steam, any suitable "carrier gas" preheated just above 1000° F. in a gas heater 15, is forced by blower 16 into the top of chamber A via hot-gas line 17 and open hot-gas-valve 18a and passes downwardly through pebble mass 9a and discharges through open-space 7a and open exhaust valve 20a to the chimney (not shown). This "carrier gas" may readily be air, gaseous products of combustion, steam, or other suitable gaseous fluid. The step of forcing hot gas downwardly through the reaction chamber is termed an "on heat" period.

Each of chambers A, B and C, when "on heat" sustains a flow of about 213,000 cu. ft./min. of air

(measured at 60° F.), the capacity of blower 16 and of preheater 15 being, of course, about 426,000 cu. ft./min. Continuous operation is maintained with this three-chamber plant; each of the chambers A, B and C is being subjected to the cracking step ("on stream") for 20 minutes, and "on heat" for 40 minutes, following each other in repetitive alternating succession. The capacity of this particular illustrative plant is 37,000 bbls./day of feed-stock treated or 23,000 barrels of motor-fuel produced.

The operation described above is used as an illustration of a manner in which the present invention can be carried out in a simple way.

The process of the present invention, it will be seen, is characterized by, among others, the following features:

1. The process is intermittent, and is carried out in two main steps.
2. In one step, heat is introduced into the fluid to be thermally altered by heat-exchanging contact with a mass of solids, and, in another step, the solids are themselves heated.
3. The rate of flow of the fluid undergoing thermal treatment is varied during the "on stream" step, the flow being controlled with respect to changing temperature distribution in the body of solids so as to bring to pass substantial completion of the thermal alteration of the fluid without material over-treatment of the latter.
4. The product formed is unstable at the temperature of formation and would be susceptible to thermal destruction were it permitted to remain heated at or near the temperature of formation for any material.
5. Each portion or "element" of the fluid to be thermally altered is heated at above a minimum and below a maximum temperature, for a period of time having determinable minimum and maximum limits.
6. Since the temperature distribution in the heat-exchanging mass of solids alters during "on stream," the rate of flow of the fluid through the mass is varied to conform with the variation in the rate of reaction caused by this variation in temperature.

Although the inventive embodiment of illustration I is workable and technically successful, it has some possible shortcomings which can be avoided by practicing the teachings of the following specific example. It should be understood that the procedure described above in Illustration I and the accompanying Figures 1 and 2 has been presented for the purpose of describing, in a simple fashion, the thermal reactions which take place when an unstable fluid is forced through a bed of pebbles, and neither the procedure nor the apparatus shown in Figures 1 and 2 is definitive of the present invention.

Illustration II

In Fig. 3, oil from supply tank 1 is forced by pump 2 through opened valve 50a, into open space 51a in reaction chamber 52a, through grate-bars 53a, into pebble-bed 54a; vertically through 54a into open space 55a; through conduit or "crossover" 56 into open space 55b; downwardly through pebble-bed 54b into open space 51b, discharging through pipe 57b, opened valve 86b, cooler 88, opened valve 58b, into product tank 59. Gases not condensed in passage through 54b and cooler 88, escape through vent 90, opened valve 87 and separator 62 into a gas holder (not shown). The fluid flow described is termed "direct stream"

and alternates with the following flow termed "reverse stream." All valves are closed. Oil from tank 1 through pump 2 is forced through opened valve 50b, upwardly through chamber 52b, into open space 55b; through 56 into 55a; and downwardly through 54a, discharging through 57a, opened valve 86a, cooler 88 and opened valve 58b into tank 59. Pebble beds 54a and 54b are of identical dimension, 42 feet in diameter and 15 feet deep. The pebbles are similar to those in Illustration I.

Fig. 4 is a diagram with degrees Fahrenheit as ordinates and x and x' as abscissae, where " x " is the distance in feet in 54a measured upwardly from 53a ($x=0$). Distance in 54a measured upwardly from 53a is plotted in the diagram from left to right. The distance between the lines MM' and NN' in Fig. 4 represents the "equivalent" length of bed 55a, 56, and 55b, i.e., time of transit of fluid from top of 54a to top of 54b is the same as time of fluid transit through 4.321 feet of bed 54a or of 54b. In Fig. 4, " x' " represents the distance in feet in 54b measured upwardly above 53b and is plotted from right to left.

The first step ("preliminary heating") of the process is: all valves are closed except 85a, 85b, 79a, 79b and 61a. Fuel from line 68 mixes with air from blower 65 in burners 78a and 78b, burns in 55a, 55b and 56, products of combustion discharging through 54a, 51a and chimney valve 61a. This combustion is controlled to heat 55a, 55b, and 56 to a selected reaction temperature, say 982° F. Blower 65 supplies 137,000 cu. ft. air per minute to each burner. Fuel feed is controlled to maintain 55a at 982° F. "Preliminary heating" as described is continued for one hour and forty-five minutes, when the temperature in 54a is as shown in curve a in Fig. 4. Valve 61a is then closed and valve 61b opened. Combustion products now pass downwardly through 54b for thirty minutes, when the temperature in 54b is as shown by curve a' in the right hand of the diagram in Fig. 4. Curve a' indicates the temperature in 56. All valves are then closed. The apparatus is then placed on a "direct stream." Crude oil of Illustration I is pumped at the initial rate of 182 bbls./min. The oil fills open space 51a, rises into contact with pebbles in 54a and is heated until at 50 the temperature, $T=207$ ° F. initial boiling occurs. As the oil reaches higher levels in 54a it is heated, vaporized and superheated, exhausting into 55a at 982° C. The vapors pass through 56 into 54b and start down through 54b. The superheated 55 and almost completely cracked vapors are cooled down in traversing 54b, temperature of the passing fluid differing little at each level from the temperature of the pebbles at that level. During cooling the cracking reaction is completed and a 60 cooled and completely cracked but not overheated condensed product trickles down through the lower levels of 54b, flowing into product tank 59. Fluid in the transit described is subjected (a) to 7.3% cracking in the lower three feet of bed 54a, 65 termed "front wave cracking"; (b) to 86.2% from $x=3$ ft. to $x=11$ ft., termed "crest cracking"; and (c) to 6.5% from $x=11$ to $x=9$, called "back wave" cracking. This "direct stream" step is terminated after twenty minutes (epoch I) during 70 which 3620 barrels of feed stock are pumped into open space 51a and 2490 barrels of product discharge into product tank 59. Direct stream is terminated at this time (epoch I). Temperatures 75 in the chambers at epoch I are shown by com-

pound curve b , b' and b'' . From the beginning to epoch I 374,000,000 B. t. u. of sensible heat have been transferred from 54a to the streaming fluid and carried into chamber 52b. This heat is represented by the area between curves a and b . Heat carried through 56 into 52b was retained in 54b and is represented by the area between curve b'' and a'' of Fig. 4, i. e., 350,000,000 B. t. u.

After epoch I all valves are closed; and valves 94a, 86a, and 58a are opened. Steam is admitted through 94a, and 1230 barrels of uncracked feed stock are drained into tank 1. Valve 86a is closed and valve 86b opened; steam from 94a sweeps through 55a, 56, 55b and 54b, hastening the draining of oil through the bottom of 51b to tank 59. All valves are then closed. The above procedure is termed "purging." It is understood that a purging operation between direct and reverse stream is optional with the operator, and although frequently desirable, cannot be considered a necessary feature of the process.

"Reverse stream" is initiated, pump 2 forcing feed stock at an initial rate of 174 bbls./min. into the reaction chamber 52b. After nineteen minutes (epoch II), during which 3300 barrels of feed stock enter 52b and 2250 barrels of heated fluid exhaust from 52a into product tank 59, the temperature of 54a, 56 and 54b is as shown by curves c , c' and c'' in Fig. 4, respectively. During reverse stream 327,000,000 B. t. u. are removed from 54b (represented by the area between b'' and c'') and 94.65% of this heat (310,000,000 B. t. u.) is returned to bed 54a. This quantity of heat is represented by the area between the curves c and b in the left diagram of Fig. 4.

Direct-stream and reverse-stream together complete a cycle in which a thermal distribution or "temperature wave" (curves a , a' and a'') has been moved up in 54a down in 54b, during "direct stream" to the position shown by curves b , b' and b'' , and then returned during "reverse stream" to position identified by compound curve c , c' , c'' . The value of $(dT/dx)^2$ at epoch II is less at each congruent point than at the beginning. By the thermodynamically irreversible transfer of heat, entropy has been generated, the temperature wave has been "spread out," the cycle is not "closed" and the final thermal wave (epoch II) differs in shape from initial shape a , a' , a'' . As the cycle is repeated the "spreading out" of the wave continues and it is necessary continually to decrease the rate of fluid flow to conform the time-temperature history of the fluid under treatment to the rate of the cracking-reaction to permit the reaction to just reach completion during transit. For example, in this illustration 4600 barrels are treated in the first cycle (by cycle is meant the combination of a direct stream step plus a reverse stream step, including whatever purging operations may optionally be employed) in 39 minutes; 4100 barrels for the second cycle in 42 minutes; and 3600 barrels in 45 minutes for the third cycle, etc.

Ultimately, as the temperature waves in 54a and 54b degenerate thermodynamically, the permissible flows of fluid will decrease, until a completely degenerate state is reached. In Illustration II, operation might continue at a greatly decreased rate of flow until the temperature distribution (represented by curves d , d' , d'') is reached. Frequently this is undesirable. After 6 cycles of the above described operation, when 20,800 bbls. of treated oil has been recovered in tank 59, oil is purged from the fluid circuit with

steam, and an "on heat" step resorted to, whereafter the operation described is repeated.

Fundamentally the operations described in Illustrations I and II do not differ from each other. In Illustrations I heat for treatment was introduced into the fluid to be treated by heat-exchanging contact with solids preheated in a manner adapted to subject the fluid in transit to a time-temperature history which caused the desired reaction to reach completion without subjecting the treated fluid to "over-treatment," and then the fluid was cooled to "quench" the reaction by a well-known type of cooler. To effect this result rapid changes in the rate of fluid flow were necessary. In Illustration II the fluid to be treated was heated as in Illustration I, and also was cooled after reaction to prevent over-treatment. The use of two reaction chambers in series to effect both the heating and the cooling of the fluid to a great extent reduced the necessary variations in rate of flow. In addition, a large recovery of heat was effected, resulting in marked improvement in the thermal efficiency of the process. It is true, of course, that interchanger 3 of Illustration I might be designed to attain an efficiency equal to that realized in Illustration II but such an interchanger is prohibitively expensive. For this reason the attainment of high efficiency by the use of a pair of reaction chambers in series is a definite improvement in the technology of the process.

Illustration III

35. In accordance with this embodiment, the process described in Illustration II is carried out as described until the temperature distribution is as represented by curves d , d' , d'' (Fig. 4). Operation of "direct-stream" "reverse stream" is continued, and the heat necessary to maintain satisfactory operation is introduced into cross-over 56 in the form of a heated "carrier gas," which conveniently may be a controlled amount of steam preheated in stoves 72a and 72b and introduced into 56 through hot "carrier gas" conduit 95 and nozzles 96. Steam enters 56 at 1500° F., and rapidly and turbulently mixes with the fluid stream there. In the particular example given the amount of steam required is 6000 lbs./min.

50. At the initiation of the operation, beds 72a and 72b are cold. They are operated alternately "on gas" and "on steam." When 72a is "on gas" fuel from 68 through open valve 66a enters burner 96a commingling with air from blower 65 entering through open valve 97a. Hot combustion products formed in open space 70a pass downwardly through the pebble bed 71a discharging through open valve 84a to chimney. Fuel and air to 96a are controlled to heat the top of bed 71a to above 1500° F.

55. When a desired upper portion of 71a is thus heated, all valves are closed. Valve 93a is opened and steam from supply line 92 is introduced into stove 72a at the bottom, passes upwardly to atmosphere through opened valve 98a until products of combustion are purged from 72a. Valve 98a is then closed, and valve 91a is opened, and steam from 92 passes upwardly through 72a, is heated substantially to 1500° F. therein and discharges through 91a, conduit 95, nozzles 96 into 56.

60. The alternate "on gas" and "on steam" steps above described for 72a are carried out identically in 72b reciprocally to provide a continuous

supply of steam at 1500° F. in 56 in controlled amount.

Illustration IV

The equipment shown in Fig. 5 is useful in carrying out the present invention in the following manner. Four chambers are provided, 101, 102, 103 and 104, having in horizontal section the relative shape represented by the rectangular inside dimensions: 18 ft. by 50 ft., 20 ft. by 65 ft., 20 ft. by 65 ft., and 19 ft. by 55 ft., respectively. Chamber 101 contains 1,960,000 lbs. of pebbles 105 screened through 1½" on 1", resting on top of 250,000 lbs. of larger pebbles 106 of three-inch average diameter. Eight 4 ft. by 4 ft. arched brick conduits 107 connect 101 with 102. Chambers 102 and 103 each contains 2,500,000 lbs. of pebbles, largely of the 3 inch size forming beds 108 and 112, respectively. Pebbles from 106 and 108 spill partly into 107, exposing "free surfaces" at their angle of repose and leaving an open space above. Wall 131 is provided with ten 4 ft. x 3 ft. arched openings 110 between open spaces 109 and 111, respectively. The right hand wall of 103 has seven 50 inch circular openings 113 connecting with conduits 114 leading to open space 115 of chamber 104. Chamber 104 encloses 3,200,000 lbs. of 1 inch-1½ inch pebbles (bed 116) carried on pebble bed 133, 450,000 lbs. of three-inch particles. The lower portion of chamber 104 contains arched constrictions 136 supported by arches 134 which provide the "louver openings" 117, 117'. Inlet 137 connects blower 132 with 117 and 117' when valve 138 is open. Air from 132 passes along 139 through open valve 140 to burner 123, fed with fuel through open valve 147 from fuel line 146 to burner 123. Chamber 101 is provided with chimney 141, chimney valve 142, a number of spray nozzles 143 fed with oil through individual valves 148 from manifold pipe 155. Spray nozzles 144 admit water through open valve 139 from water line 129. The bottom of chamber 101 is provided with drain pipe 120 and drain valve 145.

The process of cracking the crude oil used in Illustrations I, II and III with the apparatus in Fig. 5 is as follows: Step I: "On heat"—The apparatus is cold. All valves except 138, 140, 142 and 147 are closed: 480,000 cu. ft. per min. of cold air from 132 enters louvers 117, 117', passes upwardly through 116 and 112, downwardly through 108, upwardly through 105 and discharges through 142. Burner 123 is operated with 129,000 cu. ft./min. of air from 139 and 89.26 gals./min. of fuel oil from 146 and open valve 147. Products of combustion from burner 123 mix with air from 115 (after passage through 116). The amount of fuel is regulated to maintain temperature in conduits 114 at 954° F. The on-heat step is continued two hours fifty-five minutes when chimney temperature at 142 is 937° F. thereby heating 114, 113, 112, 111, 110, 109, 108, 107, 106 and 105. Valves 138, 140 and 147 are then closed. Steam is admitted by opening valve 28, and the four chambers 101, 102, 103 and 104 are purged of air with steam. Valve 142 is then closed. Step II: "On stream"—Pump 2 is started, nozzles are regulated to spray oil through spray line 143 from tank 1 in a controlled manner onto the surface of bed 105. Oil at contact with the bed is heated, vaporized, superheated and partially "cracked" as it passes downwardly through 105. Heated vapor enters 103 through 107, traverses 108, 112, 114 into open space 115 all at the mean temperature of 953° F. This vapor at 953° F. strikes the upper sur-

face of 116 and in downward passage therethrough is cooled, condensed, the condensate cooled and treated oil flows through 116 and 133 to drain through 148 and opened valve 151 and cooler 149 into product tank 150. This "on stream" step is continued at the rate of 170 barrels per minute for twenty-one minutes twenty-four seconds, during which 3000 barrels of oil have been passed into 101. During this on-stream period, 465,000,000 B. t. u.'s of heat initially in the upper 18 feet of bed 105 are transferred to 900,000 lbs. of oil, cooling this portion of 105 to 60° F. The temperature in 108 and 112 is changed only by loss of heat through the walls and by whatever heat is absorbed or produced by the "cracking reaction"; both of which items are small. More than 90 percent of the heat removed from 105 is added to the upper 17 ft. of 116. All valves are then closed. Any liquid oil in 101 is drained through 120 and opened valve 145, 152 and cooler 153 into purge tank 154. Steam from opened valve 128 is then swept through the chambers discharging through opened valve 152 into tank 154. The apparatus is then "blown back," i. e., is placed "on heat." Air traversing 116 discharges in 115 a few degrees below 953° F. A small quantity of fuel is burned at burner 123. As the "blow back" operation continues, the air from 116 discharges into 115 with falling temperature and an increasing amount of fuel is fed to burner 123 to maintain 113 at 954° F. Cold air from 132 cools 133 and the lower part of 116 to 60° F. Hot air at 938° F. from 108 enters 106 through 107, heating 106 and the lower part of 105 substantially to 930° F. "Blow back" continues at a flow of 620,000 cu. ft./min. of air from 132 for forty-two minutes, when chimney temperature at 142 is 925° F. The apparatus is then purged with steam and placed back "on stream." The previous operation is continued.

Advantages attach to the operation described in Illustration IV; (1) A constant rate of flow of 140 bbls./min. results in a "mean time of mean fluid transit" through the four chambers 101, 102, 103, 104 of 2.24, 1.56, 1.13 and 1.45 seconds, respectively. In traversing 105 at the start of the "on stream" period, an element of oil is heated rapidly and is subjected to 2.94% alteration during the 2.24 seconds the oil remains in chamber 101. The volume of vapor at entrance into 108 is 224,000 cu. ft./min. measured at actual temperature and pressure. The volume discharged from 112 at 113 is 480,000 cu. ft./min., the increase in volume being caused by the change in "mean molecular weight" of the thermally treated hydrocarbon and to the formation of methane, hydrogen, and other non-condensable gases, due to the assumed unavoidable "over-treatment." (2) The time of transit of the mean fluid element through 108 and 112 is 2.69 seconds, during which time, at the temperature of 951° F., the "cracking reaction" is completed. At the instant of the completion of the reaction the treated vapor impinges on 116, its temperature instantly is lowered and the velocity of the reaction slowed down to an immeasurable rate in less than one-hundredth of a second. As "on-stream" continues, the amount of "upstream" cracking in 105 decreases as the upper portion of the pebble bed is chilled by incoming cold oil, the cracking in 108 and 112 remains constant, and the "downstream" cracking in 116 increases as the upper portion of 116 becomes heated to 956° F. by hot vapor entering through 114.

It is an advantage of this particular embodiment of the invention (Illustration IV) that the downstream cracking in 116 increases as the upstream cracking in 105 decreases, and that each increase or decrease is small and essentially compensatory, this requiring little change in the oil pumping rate during "on stream." Operation in Illustration IV differs from Illustrations II and III chiefly in that "cross-over" 56 (Fig. 3) is functionally replaced by 107, 108, 109, 111, 112, 113 and 114 (Fig. 5). In Illustrations II and III, heating of oil, vaporization, superheating vapor, and cracking all took place in a "pebble-bed," through which the "thermal wave" was moving. In Illustration IV most of the cracking takes place in an essentially isothermal "cracking bed" and the oil heating, vaporization and superheating, with its consequent thermal wave motion, are restricted to separate beds. While this is frequently an operating advantage, it represents no fundamental difference. The fact that feed-stock is sprayed downwardly in one case and is pumped upward in the other is a casual result of engineering convenience, as is the rectangular or cylindrical shape of the chambers 52a, 52b, 101, 102, 103 and 104. In treatment of unstable fluids at elevated temperatures where there are formed products which are unstable at formation temperatures, which products decompose at rates comparable to their formation rates, an approach to isochronous fluid flow is advantageous in every type of apparatus and in every process used. Except for this, 108 and 112 might be omitted. If 102 and 103 are empty, the time of fluid transit is increased 127%. To avoid resultant over-treatment (a) the pumping rate is increased from 140 to 318 bbls./min. or (b) the chamber temperature is decreased 24° F., both temperature and rate are suitably altered, changes of little technical importance.

What would be serious, however, is the fact that were these chambers empty the heated oil would not move in "stream line flow;" eddies, vortices, and turbulence would obtain, and the flow would not be isochronous "in transit." "Dead corners" would appear in the chambers, time would be excessive, and carbon and non-condensable gas formation would increase. With empty reaction chamber, the yield would be little if any better than in present cracking process wherein open "reaction chambers" are used and fluid flow is not under control. The chief object in providing beds 108 and 112 is to direct the fluid flow in 102 and 103 and to prevent chaotic "drifting about" of fluid therein. The shape of 108 and 112 is determined by the geometry of the walls of 102 and 103 and wall 131 and by shape and "tilt" of the upper surface of 108 and 112 by the location of 107 and 110, and by the shape and size of 109 and 111.

The several fluid elements in transit from 107 to 113 should follow trajectories of such length and at such velocities that the time consumed in transit by each fluid element is the same. With proper design, it is the "time of transit" of the several fluid elements which is equal, neither the "length of path" nor the velocity separately need be or necessarily should be the same. Velocity through the bed is determined by temperature, density, and viscosity of the fluid, by size, shape, and packing of the particles or "pebbles" and by the geometry of the interstitial voids. Advance calculation of such design is not always simple or accurate. In practice, of course, fluid flow can readily be made isochronous by analyzing

fluid samples conveniently taken from selected points on the upper free surface of 108 and 112. It is usually found, however careful had been the chamber design, the screening of particles, and their "bedding down," that fluid traversing one path is either (a) "over-treated" due to too long a transit time, a defect which may be corrected by substituting larger particles along that path, or (b) "under-treated," due to too short a transit time, correctable by substituting smaller pebbles along the path to present greater resistance to fluid flow. Because the present invention can be carried out efficiently with such wide variety of structural design, the operator seldom experiences difficulty in approximating isochronous flow.

It is to be understood that for air as the carrier gas another gas such, for instance, as carbon dioxide, steam, or the like, may be employed.

Illustration V

When small scale operation is contemplated and when a minimum of apparatus is an objective, a convenient embodiment of the concepts of the present invention can be carried out with the apparatus shown in Fig. 6. After an initial "heating step" the apparatus is placed "on stream" as follows: Feed-stock from tank 201 heated to 234° F. by steam coil 202 is sprayed by pump 203 through nozzles 204 onto and into bed 208 in chamber 206, provided with insulation 207, and supported on bed 209. 207 is constructed to provide open annular space 213 through which steam at 1800° F. from ports 214 and bustle pipe 215 is introduced. Bed 209 rests on bed 210 supported upon a grid of cast iron bars 211 positioned in 206 to form open space 212. At the start of "on stream," 208 is at a selected reaction temperature, say 900° F. Oil traversing 208 downwardly is heated and progressively cracked in 208 and 209. Bed 210 was at 234° F. at the start of the "on stream" period. The treated fluid is cooled, and its reaction "quenched" as the product flows from 212 through liquid exhaust 216, opened valve 217 and cooler 218 into tank 219. Non-condensable gases discharge through 221, through open valve 222, and are stored in a gas holder (not shown). "On-stream" is continued until a selected upper portion of 208 is cooled and/or a selected upper portion of 210 is heated.

During the "on-stream" of 206, regenerator 230 is "on-gas." Air from blower 233 through opened valve 236 mixes in burner 237 with fuel from fuel lines 238 and opened valve 239; hot products of this combustion traverse pebble bed 229, discharging through open space 228, chimney 240 and opened chimney valve 241. The "on-stream" of 206 and the "on-gas" step may conveniently extend concurrently and terminate simultaneously. An "on-steam" step is now started. All valves are closed except 226, 227, 232 and 233. A regulated flow of "primary" or cooling steam from supply line 225 under control of valve 226 traverses 210 upwardly, entering 212 at 234° F. and cooling 210 to that temperature. "Secondary" or "heating" steam flows under regulation of valve 227 through bed 229, which had been heated to 1900° F. during "on gas" period. The secondary steam after heating flows through hot steam line 231, open valve 232, bustle pipe 215, ports 214, into annular space 213. The primary and secondary steam co-mingle, passing upwardly through 209 and 208, and discharging through exhaust pipe 75 234 and open valve 233. The primary steam after

traversing 210 arrives at 209 and 213, heated to 900° F., mixing with secondary steam heated to 1800° F., the mixed steam traversing 208 at 907° F. As "on steam" continues, the lower heated portion of 208 broadens upwardly. "On steam" is terminated when chimney temperature at 234 approaches 900° F. and/or when temperature at the top of 210 is cooled to 234° F. 206 is then placed "on stream" and 230 "on gas" and operation is continued by cycling these alternating steps.

Beds 208 and 209 are 10 feet in diameter and 15 feet deep, consisting each of 105,000 lbs. of $\frac{3}{8}$ inch particles of blast furnace slag. During the "on stream" step, by partially closing valve 217, pressure inside 206 is maintained at 350 lbs./sq. in. gage, and 2 barrels per minute of oil is forced through spray nozzle 204. At 900° F. molecular alteration of the oil proceeds at the rate of 0.35% per second, and the average time of the oil in the reaction zone is just three minutes.

The apparatus described above, which uses steam for a carrier gas, is particularly convenient when located in a refinery plant having an ample and inexpensive supply of steam.

Although a considerable variation in plant construction and in operation appears in the preceding illustrations, at least one feature is seen to be common to all, viz. the fluid to be treated is passed through heat-interchangers of a type exhibiting prompt "thermal response" or a high "efficiency of heat interchange." In heat-interchangers now employed in industry, fluid temperatures T_f at any position in the heat-interchanger differ greatly from the temperature of the solids, T_s , at that position. This is due to the prior art custom of designing the fluid channels of large dimensions, and of using heat-absorbing refractory of large dimensions and hence thermally "sluggish," being incapable of rapid change of temperature. Complete economic success in the conduct of the present invention is dependent on the heat-interchanging characteristics of the above-described pebble beds or of some comparably efficient type of heat-interchanger.

The velocity of the reaction causing the molecular alteration of the unstable fluids contemplated in the present invention varies greatly with T_f , not with T_s . Except in the middle of the "temperature wave front," T_s and T_f are approximately equal in the pebble-type of heat-interchanger frequently differing in practice by less than a degree or two, a fact not true in any other type of heat-interchanger used in prior practice. Such values of $(T_s - T_f)$ as have been found here are smaller than would be anticipated from experience with heat-interchangers of the usual type used variously as blast furnace stoves, or as open-hearth, glass-tank, coke-oven regenerators. The coefficient of reaction velocity in oil-cracking is so great that satisfactory temperature-time control is found to be unsatisfactory in all of the several attempts to carry out the present cracking process with heat-interchangers of the types proposed according to any of the procedures heretofore described. Conventional assemblages of standard regenerator tiles have fluid channels of large cross-section and exhibit low coefficients of heat transfer. As a result, large differences between T_s and T_f obtain throughout the regenerator and control of T_f is difficult. Near the fluid-solid interface, it is true, T_f approaches T_s closely; but at points remote from the interface,

$T_s - T_f$ is objectionably great. Furthermore, fluid velocities near the center of the channels are greater than those near the interface even when considerable turbulence is maintained. Hence "isochronous flow" cannot be approached at all closely in this type of operation; peripheral portions of the fluid streams move more slowly through the heating chamber than the more central fluid elements, remain heated longer, and are heated to higher temperatures. Over-treatment, both in time and in temperature inevitably occurs. Thus, the so-called "vapor phase" cracking processes using such "unresponsive" regenerative interchangers are recognized to deposit excessive carbon and to produce objectionably large volumes of "non-condensable" gases. These defects have been thought to be inherent in all vapor-phase cracking processes. Over-treatment has not been chemically proven to be a fundamental characteristic of low pressure thermal treatment; it is merely an observed "fact of practice" that over-treatment has been "unavoidable," which is an obvious result of the difficulty in maintaining low-density fluid (liquid or vapor) at any selected temperature, and of the decreased heat-transfer with low-density fluids and the greater departure from "isochronous" flow prevailing when fluids of low density are treated compared with fluids of greater density. The object of the present invention is to provide means for treating unstable fluids to produce unstable products at any desired pressure. Frequently the composition of the desired product depends on the reaction pressure. In the present invention, operating pressures may vary from high vacua to high pressure to accommodate a variety of feed-stocks and of products produced. Reaction chambers such as 52a and 52b in Fig. 3 are internally heated and transfer of heat through the walls is not desired. The internally insulated metallic shell remains cold and exhibits greater mechanical strength than can be realized at elevated temperatures. Since the metal is cold, reaction between metal walls and sulphur is less. Carbon deposition (reduced to a minimum in the present process) does not tend to carburize and weaken the metal. The maximum pressure is therefore limited only by structural difficulties in metal fabrication, and is not further limited by loss of metal strength due to heating, oxidation, carburization, and sulphide formation.

Although the five illustrative examples given above describe the "cracking" of petroleum, it must not be thought that the present process is concerned exclusively or even principally with that reaction. The industrial importance of producing motor fuel from petroleum compounds perhaps justifies the over-emphasis implied in the selected illustrations. Furthermore, because of the accumulated experience gained by the oil industry in carrying out the cracking reaction, it has not been necessary to discuss the chemistry of the process. On the other hand, because identification of the compounds present in the feed stock and in the altered product in these five examples is possible only in the sketchiest fashion, the pyrolysis of petroleum is not the best choice of an example for describing the basic features of the present process. In illustrations following, the carbonaceous fluid to be subjected to molecular alteration at elevated temperature is the simplest hydrocarbon known — methane. Since rather complete knowledge is had of the thermal properties of the low molecular weight compounds involved (involving less than 7-carbon

atoms per molecule) a fairly accurate quantitative description of the chemical changes taking place in the heated pebble beds can be given, and the characteristics of the present invention can be taught in satisfactory detail.

Illustration VI

The production of ethylene from methane is readily effected by passing natural gas (freed from CO_2 and H_2O) through apparatus constructed in the fashion shown in Figure 3, and operated generally as was described in Illustration II. For the present example, the pebble beds 54a and 54b are built 14 feet in diameter with an axial height of 5 feet, each bed containing 3,800,000 sandstone pebbles, screened "through one-inch" and "on one-half inch," weighing 82,000 lbs., exhibiting 36.8% voids, 42,600 sq. ft. of heat-exchanging surface, and a mean hydraulic radius of 0.073 inch. The roofs of chambers 52a and 52b are built as flat as practical and the tops of beds 54a and 54b are brought up close to the roof to reduce the volume of open spaces 55a and 55b to a minimum. In the present example the volume of 55a, 55b and the cross-over 56 is 34.5 cu. ft.

In the "preliminary heating step" the beds are at 60° F., and all valves closed except 85a, 85b, 79a, 79b and 61a. For 16 minutes 51,800 cu. ft. per min. of standard air is forced by draft blower 65 through burners 78a and 78b, while 2276 cu. ft. per min. of natural gas is fed to these burners from fuel feed line 68. Combustion in spaces 55a and 55b produces products analyzing 4.45% CO_2 , 10.20% H_2O , 9.97% O_2 and 75.38% N_2 at 1970° F., which pass downwardly through bed 54a, heating the upper portion of the pebbles to 1966° F. A "thermal wave" is established in 54a, and at the end of the 16-minute heating period the center of this wave is 48.3 inches below the surface of the bed. If L represents the distance in inches in the beds measured vertically upwardly from the grate bars 53a and 53b, and T the temperature of the pebbles in degrees Fahrenheit, then after 16 minutes of heating $T=1966$ from $L=16.5$ to $L=60$, $T=1040$ at $L=11.7$, and from $L=0$ to $L=6$ the pebble temperature T is 116° F., the dewpoint of the combustion products at which liquid water condenses from the downflowing gases. In the 10.5 inch zone between $L=6$ and $L=16.5$ the temperature gradient (dt/dL) is great, 204° F. per inch. During heating the thermal wave is "blown down" the bed at the rate of 3.03 inches per minute.

After heating 54a for 16 minutes, valve 61a is closed, valve 61b is opened and combustion products are blown downwardly through 54b for 10 minutes, heating the pebbles therein to 1966° F. from $L=34.4$ to $L=60$, to $T=1040$ at $L=29.7$ and $T=116$ from $L=0$ to $L=25$. All valves are then closed. A "direct flow" step is initiated by opening valves 50a and 61b. In the example, 1 represents a gas holder containing natural gas, assumed to be essentially pure methane, and 2 represents a 2-stage centrifugal gas blower driven by a 3600 H. P. motor. A flow of 70,000 cu. ft. per min. of gas (measured at 60° F. and atmospheric pressure) is blown upwardly through 54a from left-to-right through cross-over 56 downwardly through 54b out through 61b, to an ethylene recovery system (not shown). The natural gas passing through the apparatus experiences a pressure drop of 8.5 lbs./sq. in. The gas passes through the thermal wave front ($L=6$ to $L=16$)

bed 54a) in 0.031 seconds, through the upper heated portion of 54a ($L=16$ to $L=60$) in .049 second, traversing empty spaces 55a, 56 and 55b in .0074 second, and through the upper heated portion of 54b in ($L=34.4$ to $L=60$) in .025 second, and is cooled from 1966 to 116° F. in passing through the downstream wave front in 54b ($L=25$ to $L=34.4$) in .0273 second. In passage through the apparatus the natural gas is held at the reactive temperature (above 1700° F.) for 0.0907 second, is heated from 116° F. to 1700° F. in .027 second and is quenched back to 116° F. in 54b in .022 second. The maximum rate of heating in the upstream wave front ($L=6$ to $L=16$, 54a) is 155,000° F. per second; the maximum rate of cooling in the downstream is 204,000° F. per second. These rates of heating and cooling of course are much higher than are obtainable with industrial apparatus of any design other than that contemplated in the present invention. To a close approximation it can be said that 70,000 cu. ft. per minute of natural gas here is "instantaneously" heated to a uniform temperature of 1964° F., held in contact with pebbles not hotter than 1966° F., held at that temperature for .091 second and then "instantaneously" cooled to its initial temperature of 116° F. It is through the operation of this novel type of heating that the thermal alteration of unstable carbon compounds is effected in the present invention. Both the temperature of the reaction chamber and the time which each molecule of reactive gas is maintained at that temperature are under precise and determinable control.

On passing through bed 54a the natural gas (100% CH_4) is subjected to molecular rearrangement through the progress of four reactions involving collisions between methane molecules:

forming ethane, ethylene, acetylene, and carbon, respectively. In the present case, due to the simultaneous effect of these four reactions, the volume of gas exhausting from 54a into 55a increases from 70,000 cu. ft./min. to 79,500 cu. ft./min. (measured at 60° F.), having the composition:

	Percent by volume
C_2H_4	10.64
C_2H_2	0.73
C_2H_6	0.001
CH_4	65.18
H_2	23.45

The gas stream is subject to further expansion to 83,750 cu. ft./min. in passage through reaction chamber 52b, emerging with the composition:

	Per cent
C_2H_4	14.05
C_2H_2	1.02
C_2H_6	.001
CH_4	53.12
H_2	31.81

which gas, exhausting through open valve 61b, flows to the recovery system in which the ethylene contained (the primary product of the above thermal treatment) is extracted, e. g., by liquefaction and fractionation, or is reacted on further by chemical treatment.

At the start of the direct flow step, the molecular interchange in the gas phase described above involves the conversion in the chamber 52a (A)

16,920 cu. ft./min. of methane into 8462 cu. ft./min. of ethylene, involving the absorption of 760,000 B. t. u./min. (90 B. t. u./cu. ft. of ethylene). (B) 1160 cu. ft./min. of methane into acetylene absorbing 270,000 B. t. u./min. (467 B. t. u./cu. ft. acetylene) and (C) the deposition of 5.6 lbs. per minute of carbon by the thermal destruction of 176 cu. ft./min. of methane, absorbing 18,000 B. t. u. per minute. In addition to heating 70,000 cu. ft./min. of natural gas from 60° F. entrant temperature to 1966° F., requiring a transfer of 5,420,000 B. t. u./min. from pebbles to gas, an additional 1,048,000 B. t. u./min. of heat is absorbed from the pebbles in the bed due to the endothermic heat in the three 15 methane conversions listed above as A, B and C. The total heat transferred from the upstream pebble bed 54a to the gas is 6,468,000 B. t. u./min. (11,000 boiler horsepower). The heat required to bring the natural gas up to the reaction temperature is extracted from the wave front, and causes the thermal wave in 54a to recede upwardly in the bed at the rate of 7.46 inches/minute. The heat absorbed from the pebbles by the formation of ethylene and acetylene, and in the deposition of carbon, however, is taken from the heated portion of the pebbles (in bed 54a from L=16 to L=60), causing a drop in temperature of 61.6° F./minute. In the downstream pebble bed 54b, the conversion of methane produces, at the start of the direct flow step 3318 cu. ft./min. of ethylene and 272 cu. ft./min. of acetylene with a concurrent deposition of 1.59 lbs. of carbon. The heat absorption due to these three sources is 441,000 B. t. u./min. The total production of unsaturates per minute in the two chambers is just under a half ton, viz. 880 lbs./min. of ethylene and 100 lbs. of acetylene.

Direct flow is continued, with a "300,000 cu. ft. gas throughput," i. e., until 300,000 cu. ft. of natural gas has passed through the apparatus in the total time of 6 minutes, the rate of gas being decreased from the initial 70,000 cu. ft./min. at the start, to 30,000 cu. ft./min. at the end of direct flow. Bed 54a is cooled to 60° F. (entrant gas temperature) from L=0 to L=38. The center of the thermal wave (T=1040° F.) is at L=43.7, and the upper heated zone is only 12 inches in axial extent (L=48 to L=60). In the downstream bed 54b, however, the thermal wave has been shifted downwardly, the upper heated portion extending from L=60 downwardly to L=28.

During the direct flow step, the temperature of the heated (upper) portions of the two beds 54a and 54b decreases, as a result of the endothermic conversion of methane into ethylene, acetylene and carbon, and at the same time the velocities of these reactions are slowed down remarkably. The rate of flow of natural gas through the apparatus is diminished continuously throughout the 6-minute direct flow period, to compensate for the decreased reaction rates. The total result of the direct flow step is: 300,000 cu. ft. of natural gas enters bed 54a and 354,000 cu. ft. of altered gas discharges from 61b, this gas exhibiting an analysis (averaged for the 6-minute period) of

Per cent

C ₂ H ₄ -----	13.63
C ₂ H ₆ -----	0.001
C ₂ H ₂ -----	0.95
CH ₄ -----	54.66
H ₂ -----	30.76

In the recovery system (not shown in Fig. 3) there are extracted 3600 lbs. of ethylene and 232 lbs. of acetylene, and the gas leaving the recovery system, rid of its unsaturates, amounts to 302,300 cu. ft. of "spent gas" analyzing: 63.88% CH₄ and 36.12% H₂. The average temperature of the heated upper portion of bed 54b is 1723° F. at the end of the direct flow step. During this step 109 lbs. of carbon soot has been formed a portion of which is trapped on the pebbles amounting to a fairly uniform layer of carbon from .0002 to .0003 inch thick. A part of the carbon black formed is swept out with the gas through 61b.

The gas in the apparatus is then purged with steam, by opening valve 94a attached to a source of steam not shown, and a reheat step is initiated. All valves are closed except 61a, 25b and 99. Blower 65b discharges 51,800 cu. ft. per minute of air (at 60° F.) through open valve 99 into space 51b, which, passing upwardly through 54b, is (a) heated to the average temperature of 1718° F. and (b) cools the lower part of 54b to 60° F., at the rate of 2.90 inch per minute. Natural gas 20 is admitted from feed line 68 through open valve 83b to burner 78b, and burns in spaces 55b, 56, and 55a at the flow rate of 316 cu. ft./min. of gas having a "low" heating value of 970 B. t. u. per standard cubic foot. This reheat step 25 continues 23.5 minutes, the total fuel gas being 7432 cu. ft., corresponding to a net thermal input of 7,250,000 B. t. u. Of this, only 90.2% goes to restore the 6,540,000 B. t. u. loss in the endothermic production of ethylene, acetylene and carbon 30 black. Heat loss through the brick walls (9-inch firebrick plus 9-inch of insulating brick) amounts to 2.12%. In the direct flow step 2.42% of the heat supply was discharged through chimney valve 61b, and 5.26% of the heat was discharged 35 from 61a in the reheat step. Including time required for purging with steam at the time of valve reversals, the total cycle, direct flow, and reheat step consume 30 minutes. The daily consumption of gas in this operation is 14,400,000 cu. ft. treated, and 358,000 fuel gas, a total of 40 14,760,000 for 48 cycles per day. The products of molecular alteration of the natural gas totals 86.4 net tons (2,000 lbs.) of ethylene as primary product; with associated by-products of 5.5 tons acetylene, 2.4 tons carbon black, and 14,500,000 cu. ft. per day of discharge gas from the recovery 45 system analyzing 63.88% CH₄ and 36.12% H₂.

Illustration VII

55 With apparatus identical with that used in Illustration VI, it is possible to convert substantial amounts of methane into acetylene. The gas to be heated can be natural gas, or, without 60 serious loss of efficiency, the 63.88% CH₄ gas ("spent gas") discharged from the ethylene recovery system of Illustration VI. The preliminary heating step described in the preceding example is carried out with the exception that the fuel gas is increased from 2276 cu. ft./min. (Illustration VI) to 2830 cu. ft. in the present case, with the result 65 that the upper 44 inches of 54a and the upper 25 inches of 54b are heated to 2380° F. in place of the preceding 1966° F. The direct flow step is repeated as described, with the exception that a higher flow rate of gas is employed, i. e., 154,000 cu. ft./min. with a corresponding decrease in the time of contact between the passing gas and the heated pebbles. With increased flow the pebble 70 bed may desirably be of larger diameter, e. g.,

21

screened "through 2-inch" and "on 1.5 inch" to prevent excessive pressure drop in the passing gas stream; with the greatly increased endothermic heat absorbed in the conversion of methane to acetylene (as compared with ethylene) the rate of decrease of pebble bed temperature is greatly enhanced, causing a very large change in reaction temperature during the progress of the direct flow step. The direct flow step continues for 90 seconds, in which time 152,000 cu. ft. of "spent gas" from the ethylene recovery system is forced through the apparatus. The pebble bed temperature falls from 2372° F. to 2007° F. during this 90-second period. The volume of exhaust gas is 196,570 cu. ft. and its average analysis is

Per cent by volume				
C ₂ H ₂	9.63			
CH ₄	26.90			
H ₂	63.41			

The rate of flow is 154,000 cu. ft./min. at the start of the direct flow, but is rapidly and continuously reduced to 72,000 cu. ft./min. at the end of 90 seconds. The equilibrium composition of acetylene-hydrogen-methane mixture according to Equation 3 changes rapidly with temperature, and the rate of Reactions 3 and 4 changes even more rapidly. At the beginning, with the pebbles at 2372° F., the thermodynamic equilibrium indicates a 75% conversion of CH₄ to C₂H₂. At the end this conversion had dropped to 15%. The following figures indicates the large changes taking place in the direct flow step:

Gas passed through apparatus	38,000	76,000	114,000	152,000
Elapsed time in seconds	15	33	50	90
Gas composition:				
C ₂ H ₂ per cent	10.97	10.46	9.95	6.65
CH ₄ do	17.85	23.90	27.30	40.30
H ₂ do	71.18	65.75	62.75	53.05
Average temperatures of pebbles °F.	2311	22.07	2100	2087
Carbon deposited per cent	10.2	55.85	27.00	12.00
Average rate of flow cu. ft./min.	154,000	126,000	93,000	71,000

At the beginning, the rate of destruction of methane according to Equation 4 is high, being 36.9% in 0.01 second at 2372° F., falling to only 0.35% in 0.01 second at 2012° F. The efficiency of methane conversion to acetylene depends upon adjusting the rate of flow of gas to control the time the gas is at the particular temperature obtaining in the pebble bed, to permit the thermodynamically possible transformation of Equation 3 but to prevent excessive progress of the reaction given in Equation 4.

At the end of the 90-second direct flow step, a reheat step is carried out as described in Illustration VI. Because of the large pebbles in the present bed, the volume of air from blower 65 can be increased to 95,000 cu. ft./min. without overloading the motor driving blower 65. Fuel gas from fuel main 68 is increased to 812 cu. ft./min. of natural gas and the reheat step continues 18 minutes and 30 seconds. With a 30-second steam purging operation before and after the direct flow step, a complete cycle (direct flow-steam purge-reheat-steam purge) consumes 18 minutes, permitting 80 cycles per day. The gas during direct flow discharging through 61b is fed to an acetylene extraction plant (not shown) in which 1300 lbs. of C₂H₂ is recovered from each cycle, totalling 52

22

tons per day, which, added to the 5.5 tons recovered in the ethylene recovery system (of Illustration VI) makes a total of 57.5 tons of acetylene. There is produced 7.8 tons of carbon black per day, some 4 to 5 tons of which may be removed from the gas discharging from 61b, to prevent clogging the acetylene recovery system. After extracting the 52 tons of acetylene from the daily discharge of 15,600,000 cu. ft. from 61b, the acetylene recovery system discharges 14,100,000 cu. ft. of "spent gas," analyzing CH₄ 29.79 and H₂ 70.21. The total gas used in Illustration VII is 12,100,000 cu. ft. per day (treated in 54a and 54b) plus 1,250,000 cu. ft. per day of fuel gas (in the reheat step).

Illustration VIII

The conversion of methane into hydrogen according to Equation 4 of course is easily realized by the present invention. The direct conversion of natural gas to hydrogen gives a maximum yield. The "spent gas" from Illustration VII, however, can readily enough be converted into H₂ with the concurrent production of carbon black. If it is desired to produce hydrogen as nearly free as possible from methane, the fuel gas feed in the preliminary heating is increased to heat the pebbles to the highest practical temperature. With usual firebrick and sandstone, or silica pebbles, 2600° F. is a suitable temperature. At this temperature the speed of methane decomposition is high enough (40,000% per second) so that equilibrium is reached without need of slowing down the rate of blowing in order to realize minimum methane in the exhaust hydrogen. At 2600° F. the equilibrium percentage of CH₄ in the altered gas is 0.133%, with 99.867% H₂. By pushing the temperature up to a high value (using dead burned magnesite "pebbles" and basic refractory brick for lining), it is possible to lower this residual methane somewhat. For example, with the pebbles heated to 3100° F., the residual thermodynamically minimum methane is 0.055%. Above this temperature, reaction takes place between the carbon deposited on the magnesite (or dolomite) pebble and on the basic refractory, producing magnesium vapor and carbon monoxide. Because of the very rapid quenching in the wave front in bed 54b on direct flow, re-oxidation of the magnesium metal by CO is inhibited, and the hydrogen gas becomes contaminated with CO, a more serious impurity in the hydrogen than the methane.

In many industrial gases the carbon black produced is of greater importance than the hydrogen. Superior quality of carbon black can be produced at lower temperatures, and particularly by the rapid heating in the upstream wave front (bed 54a). At the lower temperatures the rate of blowing must be decreased in conformity with the sluggish rate of the reaction given in Equation 4. The carbon black or powder, or soot, produced is largely blown out of 61b with the emergent hydrogen, but some remains lodged on the pebbles. This coating of carbon is burned out during the reheating step, thereby diminishing the amount of fuel gas required in this step.

As an alternative procedure, the pair of stoves 72a and 72b (Fig. 3) can be operated as was described in Illustration III and used to preheat hydrogen gas, supplied in Illustration VIII, through conduit 92 (marked "steam" in the drawing) through which steam was fed to 72a and 72b in alternate steps in Illustration III. In the present example hydrogen produced in the process is fed

23

back through 92 to pass upwardly through the heated pebble beds 71a and 71b to supply heated hydrogen through hot gas line 95 and nozzles 96 into the cross-over 56, thereby supplying to the pair of reaction chambers 52a and 52b the heat absorbed in the endothermic reduction of methane. In this operative procedure, the re-heat step is omitted and the reaction chambers 52a and 52b are operated alternately on "direct flow" and "reverse flow" as described in Illustration II. In this manner, no gas passes through 52a and 52b except CH₄ and H₂. The carbon dust deposited on the pebbles accumulates, and when the interstices between the pebbles become restricted, the beds of pebbles are removed from the reaction chambers 52a and 52b and replaced with other pebbles, and the carbon recovered from the mass of pebbles after removal.

In Illustrations VI, VII and VIII, three reactions are explained, all three of which, as it happens, being more or less endothermic, causing a decrease in the temperature of the pebble bed during direct and reverse flows, and requiring a "reheating" step in the operation of the auxiliary stoves 72a and 72b to supply the compensating heat by the introduction of a highly heated gas (steam in Illustration II, hydrogen in Illustration VIII). The application of the present process is not confined to endothermic reactions. When the desired molecular alteration of the fluid to be treated generates heat instead of absorbing it, no reheating step is required, nor is it necessary to supply auxiliary heat from the pair of stoves 72a and 72b. The reaction between acetylene (produced in Illustration VII) and ethylene (produced in Illustration VI) is an important example of a strongly exothermic reaction.

Illustration IX

Because of the low velocity of the reaction

the apparatus shown in Fig. 5 and described in Illustration IV is convenient for use in the present example. Pebble beds 105, 108, 112 and 116 are heated as was described (Illustration IV) to the temperature of 1652°, in the preliminary heating step. After purging the apparatus with steam, and purging the steam with hydrogen, gas blower 2 (which was an oil pump in Illustration IV) forces 10,000 cu. ft./min. (measured at 60° F.) of a gaseous mixture of 57% ethylene and 43% acetylene (by volume) into the open space above pebble bed 105 in chamber 101. The gas mixture flows through beds 105, 108, 112, and 116 in series and discharges through exhaust pipe 148 and open valve 151 into the diolefine recovery system 149 and 150. The time required for any portion of the gas stream to traverse the four beds is 3 minutes and 9 seconds. The volume of the gas mixture discharging into 149 is 8600 cu. ft./min. and its composition by volume averages

$$C_4H_6 = 24.40$$

$$C_2H_4 = 33.70$$

$$C_2H_2 = 33.75$$

$$H_2 = 8.15$$

Two reactions take place in the pebble beds, (A) 2100 cu. ft./min. of acetylene combines with an equal volume of ethylene to form 2100 cu. ft./min. of 1.3 butadiene (all volumes measured at 60° F.) causing the generation of 367,000

24

B. t. u./min. of exothermic heat, and (T) 700 cu. ft./min. of ethylene is converted into an equal volume of acetylene plus an equal volume of hydrogen according to equation

Equation 6 being of course merely Equation 3 minus Equation 2, and thus does not represent any additional chemistry. This conversion of ethylene to acetylene is endothermic, absorbing 147,500 B. t. u./min. The walls or the four chambers in Fig. 5 are constructed with 9-inch fire-brick enclosed in 27 inches of insulating brick, which maintains the heat loss through the walls to as little as 55,000 B. t. u./min. The net generation of heat in the beds is therefore 164,500 B. t. u. per minute, causing the pebble temperature to rise at the rate of 0.0515° F. per minute. The direct flow step is continued for 12 hours, during which time the temperature of the pebble beds rises 37.2° F. The average bed temperature at the termination of the direct flow step is 1689° F. During this step the upstream wave front is blown downwardly in bed 105 13 feet 6 inches, the rate of travel of the wave being constant throughout at 0.225 inch per minute.

The following step is not properly termed a "reheating step" but perhaps properly enough a "blow-back" step. After purging the chambers of the gas with steam, blower 132 is started, valves 138 and 142 opened, 118 and 151 closed, and 604,000 cu. ft. of air is blown through the four beds in series order, 116, 112, 108 and 105, for thirty minutes, thereby "blowing" the thermal wave in bed 116 upwardly and the thermal wave in bed 105 upwardly 13 ft. 6 inches, returning these wave fronts to the positions they occupied at the beginning of the direct flow step. In order to dispose of the exothermic heat generated by the reaction (Equation 5) between C₂H₂ and C₂H₄, 13,000 cu. ft. of the air from blower 132 is bypassed through conduit 139 and open valve 140, which "auxiliary chilling air" enters conduit 114 at 60° F. commingling with the remaining 590,000 cu. ft./min. of air, leaving open space 115 at 1688° F., thereby lowering the temperature of the gas entering 112 to 1652° F. The apparatus is purged of air with steam through 128 or by spraying water on the top of 144 through open valve 130 in conduit 129. The apparatus is then purged of steam with hydrogen and a direct flow step immediately reinitiated. The "cycle" of direct flow, steam-purge, blow-back, steam-purge, hydrogen purge, consumes 12 hours and 35 minutes.

The total gas per day entering the butadiene recovery system 149 averages 11,740,000 cu. ft., containing 2,860,000 cu. ft. of 1-3 butadiene (measured at 60° F.) equal to 412,000 lbs. or 206 daily tons (2000-lb.). The daily feed is 13,690,000 cu. ft. of mixed "fluid to be altered," containing in the above described direct flow step 7,800,000 cu. ft. of ethylene and 5,890,000 cu. ft. of acetylene. The "spent gas" discharged daily from the butadiene recovery system averages 8,880,000 cu. ft. of acetylene-ethylene-hydrogen mixture of analysis: C₂H₂ 44.65, C₂H₄ 44.60, and H₂ 10.75%. The gas returned from 149 and 150, stripped of its diolefine content, can be recycled by adding, as make-up, 2,870,000 cu. ft. of ethylene (143 tons) and 1,930,000 cu. ft. of acetylene (65.6 tons). This process of re-cycling gas from the system 149 and 150, results in the continuous build up of H₂ in

the reactant gas, and results in a loss of tonnage, since the "percentage conversion" of olefines and acetylene to diolefine is decreased due to the decrease in partial pressure of C_2H_2 , C_2H_4 and C_4H_6 in Equation 5.

Because of the low gas flow through the pebble beds in this example, the pebbles used may preferably be screened through $\frac{3}{8}$ inch and on $\frac{1}{4}$ inch. The total weight of pebbles in the four chambers (Fig. 5) is 5670 net tons. The heat exchanging surface of pebbles exposed to the gas is 13,160,000 sq. ft. (300 acres). The time of passage of the gas through the heated zone is just over three minutes. Such a long heating time for the gas is necessary because of the low velocity of the butadiene formation reaction, when uncatalyzed. If the pebbles consist of quartz or pure silica sandstone, e. g., "firestone" from northern Ohio, substantially free from iron oxide, the amount of surface catalysis is relatively low. But with the enormous area exposed to the gas and with the small "mean hydraulic radius" of the gas channels (0.03 inch) even so-called catalytically inert silica, or clay, may readily double and triple the "uncatalyzed reaction velocity" upon which the above example is based. In illustrations I to VIII, supra, the uncatalyzed reaction velocities were very high, and some difficulty is experienced in shortening the time-at-temperature, i. e., the time at which the reactive fluid is held at reactive temperature (T. A. T.), sufficiently to prevent excessive decomposition of reactants and products. In Illustration IX, however, the normal reactive velocity is so slow that very large scale apparatus is required for the small tonnage of product (200 tons/day). In the present example speeding the normal reaction rate is desirable. No particularly excellent catalyst is desired, nor is it difficult to discover. Silica, clay, glass and copper are not catalytically active. Finely divided iron, nickel and cobalt do speed up the reaction from 20 to 30-fold. In the case of porous sandstone (running from 80 to 95 lbs. per cubic foot) pebble beds, in which the sandstone contains substantial amounts of Fe_2O_3 , the Fe_2O_3 is reduced to the metallic state by means of the H_2 and CH_4 of the passing gas stream and by the carbon-black deposited in the pores of the sandstone lumps. When the large tonnages of heat exchanging pebbles are used, it is not, in every case, a desirable investment to save money on size of apparatus by spending money on artificially catalytic material. In Illustration IX, considerable improvement in recovery of diolefines can be effected by soaking the pebbles in solutions of iron, chromium, nickel and/or cobalt salts before placing them in the apparatus. The pebbles are heated to decompose the salts by oxidation to oxides, then passing H_2 and/or CH_4 gas through the apparatus to remove the oxygen. Operation at lower temperature is then possible with a substantial increase in the amount of C_2H_4 and C_2H_2 converted into C_4H_6 . For example, at the pebble bed temperatures given below the equilibrium composition of a 50-50 mix of C_2H_4 and C_2H_2 is given:

Pebble Bed Temperature, °F.	1200	1400	1600	1800
Equilibrium Composition of the gas:				
percent C_4H_6 -----	91.00	74.00	43.00	22.00
percent C_2H_2 -----	4.50	13.00	28.50	39.00
percent C_2H_4 -----	4.50	13.00	28.50	39.00

Increasing the conversion of C_2H_2 and C_2H_4 to C_6H_6 decreases, of course, the difficulty of extracting the butadiene from the gas mixture entering the recovery system 149 and 150. The rate of conversion of ethylene to acetylene (Equation 6), however, is generally increased at the same time as the reaction of Equation 5 is catalyzed, and it is the reaction equation which produced H_2 that accumulates in the recycled reactant gas, causing operating difficulties, loss of materials and conversion costs.

Illustration X

15 The exothermic heat generated in the production of 1-3 butadiene, illustrated above, was not very great (causing a rise of temperature of only $.052^{\circ}$ F. per minute). The conversion of the acetylene produced in Illustration VII into benzene is of considerable industrial importance and is a better illustration of a strongly exothermic reaction carried out by the methods of the present invention. Satisfactory operation can be realized at high temperature, with correspondingly short time-at-temperature, T. A. T.

20 At atmospheric pressure, C_2H_2 polymerizes to C_6H_6 with the following equilibrium composition:

Temperature of Pebble Bed, °F.	1800	1900	2000	2100	2150
Percent of C_6H_6 -----	91.0	83.5	67.2	37.0	22.0
Percent of C_2H_2 -----	9.0	16.5	32.8	63.0	78.0

30 Both the reactant C_2H_2 and the product C_6H_6 are completely unstable, the rate of their decomposition being high at all temperatures listed above. A convenient reaction temperature for the purpose of illustration is 2000° F. Apparatus constructed as shown in Fig. 3 will serve, with the pebble bed diameter 10 feet; bed depth 3 feet; pebbles screened through $1\frac{1}{2}$ inch on 1-inch; weight of pebbles 21,000 lbs, each bed; heat exchanging surface 7500 sq. ft. In the preliminary heating step carried out as previously described, the upper 18 inches of beds 54a and 54b (Fig. 3) are heated to 2000° F., and a direct flow step is initiated, blower 2 forcing 3000 cu. ft./min. of acetylene through the two beds as described in Illustration VI. The volume of the voids in the hot portion of the pair of beds is 87 cubic feet, and the T. A. T. for the gas is 0.47 second. At $2,000^{\circ}$ the rate of decomposition of C_2H_2 into carbon and hydrogen is 5.8% per second, causing the production of 2.54 lbs. of carbon black per minute and 81 cu. ft. of hydrogen per minute. The volume of gas emerging from exhaust 61b and delivered to the benzene scrubber is 16.35 cu. ft. per minute with the composition (by volume):

	Per cent
C_6H_6 -----	41.58
C_2H_2 -----	24.37
H_2 -----	34.05

60 65 The high hydrogen content of the exit gas is due to the excessive production of carbon and hydrogen from the thermal destruction of the C_6H_6 during its formation, amounting to 33 lbs. per minute in addition to the 2.5 lbs. of carbon formed from the acetylene during its conversion to benzene. The production of benzene at the rate of 681 standard cu. ft. per minute generates 507,500 B. t. u. per minute in the pebble bed. The decomposition of acetylene into hydrogen and

carbon is endothermic, absorbing 22,000 B. t. u. per minute. The net heat generated is 485,500 B. t. u. per minute, causing a rise in bed temperature of 81° F. per minute. Direct flow continues for 3 minutes and 30 seconds, the apparatus is purged with steam, and a "blow back" step initiated in which 15,700 cu. ft./min. of air from blower in 65b is forced through open valve 99 into 51b upwardly through 54b, the air being heated to 2283° F., the final temperature of the beds 54a and 54b, after being heated 81° F. per minute for 3½ minutes. Auxiliary cooling air from blower 65 is forced through open valve 79b into space 55b, mixing there with the main stream of heated air emerging from bed 54b. The amount of auxiliary air from blower 65 is adjusted to maintain the temperature of the bed 54a at 2000° F. Because of the oxidation of the carbon trapped on the pebbles there is a tendency to an undesired rise in temperature in 54a above 2000° F. This can be controlled by admitting steam through open steam valve 94a. The endothermic reaction between H₂O and carbon is used to control the temperature in bed 54a. The blow-back step translates the thermal wave in 54b upwardly at the rate of 2 inches per minute. During the direct flow step the wave is forced downwardly at the rate of 1.24 inches per minute. When the blow-back step has continued for 2 minutes and 12 seconds, blowers 65 and 65b are stopped, the apparatus purged with steam, the steam purged with H₂ and the direct flow re-initiated.

The time of the complete cycle is 6 minutes and 30 seconds, permitting 220 cycles per 24-hour day. The volume of the exit gas through 61b entering the benzene scrubber (not shown) is 5722 cu. ft. per cycle or 1,256,000 cu. ft. per day. The benzene content of the exit gas is 54.3 net tons, i. e., 14,560 gallons per day, the benzene yield normally obtained from a battery of 230 by-product ovens coking 4800 tons of coal per day.

The daily discharge of benzene-free "spent gas" from the scrubber is 735,000 cu. ft. per day with the composition 41.70% C₂H₂ and 58.30% H₂, which may be separated, returning the acetylene for recycling and providing 424,500 cu. ft. of hydrogen as by-product.

The ten examples of practice described above illustrate the principles of the present invention as applied to the thermal alteration of petroleum to produce motor fuel and other petroleum products (Illustrations I to V), and to the heat treatment of methane and/or natural gas (Illustrations V to X) and to the products of such treatment.

The present invention comprises a thermal cycle exhibiting a close approach to thermodynamic reversibility and is not directed towards nor confined to any particular reaction. The method of operating the process as applied to the particular chemical reactions chosen for illustration has been described in considerable detail in which quantitative values for temperatures, rates of flow, gas composition, dimensions of the apparatus, etc., have been given. In any particular case the choice of operating variables, principally reaction temperature and time-at-temperature (T. A. T.), is governed by the changes of enthalpy (ΔH°) and entropy (ΔS°) of the reaction on the one hand and the rates of the reaction itself on the other hand. At the temperature at which the desired reaction proceeds with satisfactory velocity, all of the carbon

fluids considered above are thermodynamically unstable, i. e., in the binary system, carbon-hydrogen, the only stable state is the two-phase products solid carbon and hydrogen gas. Because of the large area of heat exchanging solid surface with which the gas is in contact in this process a complete absence of catalytic effect is difficult to obtain in practice. It is therefore impossible to specify with sufficient accuracy the proper T. A. T. for each reaction temperature. The figures used in the preceding examples are based upon so-called "uncatalyzed" reactions, which are somewhat difficult to attain even in carefully constructed laboratory apparatus. The operator of the present process must be familiar with both the thermodynamic equilibria involved, but must make the proper engineering compromise between such equilibria and with the actual reaction rates obtaining in a given pebble bed.

In the case of the "cracking" of petroleum, the proper time-at-temperature has been learned from past experience, to a large degree. With regard to many of the other reactions, even the thermodynamic properties of the system have not been widely known. In each of the equations given above the equilibrium composition can be determined from the free energy equation

$$-RT \log_e k = \Delta H^\circ - T \Delta S^\circ$$

when *k* is the equilibrium constant, *R* the gas constant, and *T* the temperature in degrees Kelvin. In the case of the six reactions discussed in Illustrations VI to X, at the temperature at which the reactions were carried out, the enthalpy and entropy charges are:

Equation	Reactants	Products	ΔH°	ΔS°	T
40 1	2CH ₄	C ₂ H ₂ +H ₂	15,820	-2.81	---
2	do	C ₂ H ₂ +2H ₂	53,180	34.05	1,370
3	do	C ₂ H ₂ +3H ₂	97,150	64.42	1,570
4	do	2C+4H ₂	41,600	50.95	1,300
5	C ₂ H ₂ +C ₂ H ₄	C ₄ H ₆	-36,720	-28.50	1,190
6	3C ₂ H ₂	C ₆ H ₆	-155,600	-109.6	1,368

ΔH° in calories per mol. and ΔS° in calories/°C. per mol.

Because the entropy charge in Equation 1 is negative while ΔH° is positive, no substantial amount of ethane can be produced by thermal alteration of methane. The production of ethylene and acetylene, however, is readily realized, ΔH and ΔS both being positive. The percentage conversion increases with temperature, but so also does the rate of decomposition of all three compounds CH₄, C₂H₄ and C₂H₂. Satisfactory results are attained by permitting an extremely brief time-at-temperature. Reaction 4 proceeds with no difficulty at all at elevated temperature, no maximum limit being imposed on the T. A. T., although the persistence of a stable tenth of a per cent of methane at maximum temperature proves an impurity if high purity hydrogen is required. Reactions 5 and 6 with ΔH° and ΔS° both negative attain best conversions at low temperatures. The velocities of both reactions are objectionably slow and percentage conversion must be surrendered in order to keep the time-at-temperature at a reasonable figure.

The more difficult factor in the operation of the present process is the determination of the reaction rate. For high molecular weight paraffins an expression can be given as follows:

$$\log_{10} v = 42.5 \log_{10}(T/1000) + 5.177 - 8.360/N$$

where *v* = velocity in per cent per second, *T* is

temperature degrees Kelvin, and N is the number of carbon atoms in the paraffin. Rates calculated from this equation agree with an average error of about 5° C. For the higher temperatures and for the lower molecular weight compounds, no general expression can be found. Annoying variations in observed reaction rates are partly due to the difficulty of avoiding surface catalysis. In actual operation, however, an analysis of the gases leaving the reaction chambers will in every case indicate to the operator whether his time-at-temperature is too long.

Quite a number of important compounds, formed from the several hydrocarbons produced by the preceding examples, can be manufactured by subjecting CH_4 , C_2H_2 , C_2H_4 , C_6H_6 , C_4H_6 , etc., in the presence of each other and/or with H_2O , HCl , Cl_2 , etc., to thermal treatment by the methods of the present process as described above. Among such compounds may be noted, phenol, toluol, styrene, isoprene, chloroprene and 2-phenyl-1-3-butadiene, according to the following reactions:

- (7) $\text{C}_6\text{H}_6 + \text{H}_2\text{O} \rightarrow \text{C}_6\text{H}_5(\text{OH}) + \text{H}_2$ (phenol)
- (8) $\text{C}_6\text{H}_6 + \text{CH}_4 \rightarrow \text{C}_6\text{H}_5\text{CH}_3 + \text{H}_2$ (toluene)
- (9) $\text{C}_2\text{H}_4 + \text{C}_6\text{H}_6 \rightarrow \text{HC}(\text{C}_6\text{H}_5) : \text{CH}_2 + \text{H}_2$ (styrene)
- (10) $\text{C}_4\text{H}_6 + \text{CH}_4 \rightarrow \text{H}_2\text{C} : \text{C}(\text{CH}_3) : \text{CH} : \text{CH}_2 + \text{H}_2$ (isoprene)
- (11) $\text{C}_4\text{H}_4 + \text{HCl} \rightarrow \text{H}_2\text{C} : \text{CCl} : \text{CH} : \text{CH}_2$ (chloroprene)
- (12) $\text{C}_4\text{H}_6 + \text{C}_6\text{H}_6 \rightarrow \text{H}_2\text{C} : \text{C}(\text{C}_6\text{H}_5) : \text{CH} : \text{CH}_2 + \text{H}_2$ (phenyl butadiene)

For a more detailed description of the thermal changes taking place in the pebble beds employed in the present process reference is made to my U. S. Patents Nos. 1,940,371 and Reissue 19,757.

I claim:

1. The process of decreasing the average molecular weight of a fluid reactant containing at least one carbonaceous component thermodynamically unstable and rapidly reactive at an elevated reaction temperature to produce a product of reaction by heating the reactant to the said temperature for a minimum length of time, sufficiently long to effect the said reaction to a predetermined extent, and for a maximum length of time, so short that an undesired amount of decomposition of reacted product is inhibited, which comprises, as a thermal adjusting step, establishing in thermally insulated, broadly-extended, freely-bedded masses of relatively small, thermally responsive, refractory, solid, mineral particles a spatial distribution of temperatures comprising five zones of temperature in immediate mutual juxtaposition consisting in a cold zone, a thermal wave, a central hot zone, a second thermal wave and a second cold zone, the said first and second cold zones being substantially isothermal at such low temperatures that molecular alteration of the reactants and products are slow, the hot zone being substantially isothermal at the said elevated reaction temperature, the first thermal wave exhibiting large positive thermal gradients measured in the direction of fluid flow, and the second thermal wave exhibiting large negative temperature gradients similarly measured; and, as a first operating step, forcing the fluid reactant to enter the first cold zone, to traverse the first thermal wave whereby the reactant is heated to reaction temperature, controlling the rate of fluid flow, whereby the duration of exposure of

the reactant in its passage through the hot zone is delimited between the said maximum and minimum, whereby the reacted product is rapidly quenched to inertness in transit through the second thermal wave, and whereby the reacted product is discharged through the second cold zone; continuing the first operating step while as (1) the two thermal waves are convectively displaced in the direction of fluid flow, (2) the first cold zone increases in spatial extent, (3) the second cold zone decreases, and (4) the central hot zone is subjected to displacement through the particles; terminating the first operating step before the disappearance of the second cold zone; and, as a second operating step, forcing the fluid reactant to traverse the said five zones in reverse sequence, whereby the translation of the two thermal waves and of the hot zone is reversed in direction and while as the second cold zone increases and the first cold zone decreases; continuing the process as a repetitive alternating succession of first and second operating steps, while as the hot zone is repeatedly reciprocated within the massed particles, the spatial extent of the two thermal waves continually and irreversibly increases, and the temperature gradients therein decrease in absolute magnitude; and terminating the described succession of first and second operating steps when the thermal waves cease sharply to define the said five zones.

2. The process described in claim 1, wherein, after the termination of the alternating succession of first and second operating steps, due to the thermodynamic degradation of the said thermal waves, the initial temperature distribution is restored by a repetition of said thermal adjusting step.

3. The process of heat treating a carbonaceous fluid reactant to form reaction products of altered average molecular weight which comprises, as a thermal adjusting step, establishing a space-gradient of temperature within thermally insulated, enchambered masses of chaotically deposited, relatively small, heat-resistant, solid, mineral particles, the said distribution being characterized by the mutual juxtaposition of a terminal cold zone, an intermediate transition zone, a central hot zone, a second intermediate transition zone and a second terminal cold zone, the temperature of the said cold zones being sufficiently low to inhibit appreciable reaction, the temperature of the central hot zone being sufficiently high to promote a rapid rate of reaction, the two said transition zones exhibiting large thermal gradients; as a first operating step, causing the fluid reactant to traverse the said five zones in the order named whereby it is heated, reacted and quenched in the said transit; as a second operating step, causing the reactant to traverse the said five zones in reverse order; continuing the process in an alternating cyclic succession of the said first and second operating steps, while as the central hot zone reciprocates in the massed particles and the two transition zones are thermodynamically degraded and increase in spatial extent; terminating the said cyclic succession of operating steps when as, due to the said expansion of the transition zones, insufficient space remains for further reciprocation of the central zone; and thereafter re-establishing the initial thermal distribution by repeating the said thermal adjusting step.
